Specification for Design.

Patented Mar. 7, 1922.

Application filed October 10, 1921. Serial No. 506,882. Term of patent 7 years.

To all whom it may concern:

Be it known that I, AUGUST DLOUHY, citizen of the United States, and a resident of Wallingford, county of New Haven and State of Connecticut, have invented a new, original, and ornamental Design for a Paper Weight, of which the following is a specification, reference being had to the accompanying drawing, forming a part thereof.

In said drawing:

The figure is a perspective view of an ornamental paper weight embodying the design of my invention.

I claim—

The ornamental design for a paper weight substantially as shown.

AUGUST DLOUHY.
